HOLLOW WALL CARTON FORMED OF TWO
BLANKS

William P. Frankenstein, Cincinnati, Ohio

Application January 8, 1946, Serial No. 639,767

13 Claims. (Cl. 206—45.22)

1

This invention relates to improvements in cartons or boxes and particularly to cartons or boxes of the knocked-down type.

One of the chief objects of the present invention is the provision of a knocked-down box which is provided with a lid and in the trade may be referred to as of the break-back lid type.

Another object of this invention is the provision of a box or carton as above referred to which is provided with hollow or double walls having the wall members thereof spaced from one another.

Another object of this invention is the provision of a carton or box as above referred to in which the major portion of the carton, including the hollow walls, at three sides thereof and lid, are formed from a single blank while the remaining wall is formed from a second blank.

A further object of the invention is the provision of a carton of the class above referred to and including in its final assembled form, four hollow walls and lid in which the carton proper is formed from a single blank and which carton includes three hollow walls and one plain wall and in which the fourth hollow wall and lid are formed from a supplementary or second blank.

A still further object of this invention is the provision of a plurality of blanks, each provided with cooperating means whereby they are detachably connected to one another to provide a hollow wall carton including a lid and which lid is of the break-back type to act as an easel for display purposes for the box proper.

Other objects and advantages of the present invention should be readily apparent by reference to the following specification considered in conjunction with the accompanying drawings forming a part thereof and it is to be understood that any specifications may be made in the exact structural details there shown and described, within the scope of the appended claims, without departing from or exceeding the spirit of the invention.

In the drawings:

Fig. 1 is a perspective view of the closed carton of this invention.

Fig. 2 is the perspective view of the carton of Fig. 1 set up for display purposes.

Fig. 3 is an extended plan view of a blank from which the major portion of the carton of Figs. 1 and 2 is formed.

Fig. 4 is a view of the blank of Fig. 3 showing it in each of two advanced stages of its manufacture.

2

Fig. 5 is a sectional view through the blank in its final form prior to shipment to the user taken on line 5—5 on Fig. 4.

Fig. 6 is a plan view of a blank which forms a part of the carton of Figs. 1 and 2 and cooperates with the blank of Fig. 3.

Fig. 7 is a perspective view of the blank of Fig. 6 in set-up condition.

Fig. 8 is a perspective view showing the blanks of Figs. 3 and 6 in the process of assembling to make the carton of Figs. 1 and 2.

Fig. 9 is a plan view of a blank in two stages of assembly which takes the place of the blank of Fig. 6 and part of the blank of Fig. 3 and therefore illustrates a modification in the carton as a whole.

Fig. 10 is a perspective view of the blank of Fig. 9 in erected position.

Fig. 11 is a plan view of a blank showing a further modification in the details of construction of a carton forming the subject of this invention.

Fig. 12 is a plan view of a modification blank for use with the blank of Fig. 11, said blank of Fig. 12 taking the place of the blank of Fig. 6.

Fig. 13 is a perspective view showing the blank of Fig. 12 in a set-up or assembled position.

Fig. 14 is a perspective view showing the blanks of Figs. 11 and 12 in the process of erection to provide a modified carton or box of the kind illustrated in Figs. 1 and 2.

Throughout the several views of the drawings similar reference characters are employed to denote the same or similar parts.

As was noted above, this invention pertains to a knocked-down carton provided with an integral lid for enclosing the contents of the carton for packing and shipping purposes and which lid is further utilizable as an easel for display of merchandise on a counter and from the carton thereof of individual sales may be made. The carton of this invention will find its use in the packing and shipping of single items as well as in the packing and shipping of a plurality of items; as an example of the plurality of individual items; golf balls, flash light batteries and the like, and which items may be dispensed singly from the carton as distinguished from a bulk or full carton sale. The carton in its use as an enclosing and shipping container is best illustrated in Fig. 1, while, when in use as for displaying merchandise therein and from which sales may be made, is best illustrated in Fig. 2.

As intimated, above, the carton of this invention is formed of two blanks which may be re-

ferred to as a major blank and a minor blank, the former making up the major portion of the carton while the latter makes up the minor portion thereof. The major blank, of one form of the invention, is illustrated most clearly in Fig. 3, while the minor blank is illustrated most clearly in Fig. 6 and these figures will now be described in detail along with the disclosure in Figs. 1, 2, 4, 5, 7, and 8.

The major blank of Fig. 3 comprises a bottom panel 15 defined in its entirety by score or fold lines 16, 17, 18, and 19. The score or fold lines 17 and 19 may be referred to as the sides of the carton and respectively hingedly connect to the bottom panel similar extensions 20, and 21 which form the side walls of the carton. The score or fold lines 16 and 18 may be respectively referred to as the front and back of the carton and respectively hingedly connect to the bottom panel 15 extensions 22 and 23 which extensions respectively form the front wall of the carton and the back wall and cover for the carton.

The front wall extension 22 is provided with a plurality of score or fold lines 24, 25, 26, and 27, thereby forming in said extension panels 28, 29, 30, 31 and 32. Each of these panels is of a length equal to that of the bottom panel 15 between its sides 17 and 19. The panel 28 in the erected cartons form the front wall outer wall member and has its ends defined by score or fold lines 33 and 34, respectively extensions of score or fold lines 17 and 19. The panel 29 forms the front wall top wall member and its length is defined by cut lines 35 and 36 respectively in alignment with the score or fold lines 32 and 33. The panel 30 in the erected carton forms the front wall inner wall member and has its ends defined by score or fold lines 37 and 38 respectively in alignment with cut lines 35 and 36. The front wall inner wall member 30 has hingedly connected therewith through the score or fold lines 37 and 38 tucking flaps 39 and 40 respectively hingedly supporting spacer flaps 41 and 42 through score or fold lines 43 and 44. The said front wall inner wall member 30 is further provided respectively adjacent its ends with elongated apertures 45 and 46 which extend inwardly of the panel from its score or fold lines 25. The panel 31 in the erected carton constitutes the front wall bottom wall member while the panel 32 forms the gluing flap for completing the front wall.

The blank extension 23 from the score or fold line 18 is likewise provided with a plurality of score or fold lines 47, 48, and 49 thereby forming in said extension 23 panels 50, 51, 52, and 53. The length of these panels of extension 23 is substantially equal to that of the bottom panel 15 between its score or fold lines 17 and 19. The panel 53 in the erected carton forms the back wall outer wall member and has its ends defined by score or fold lines 54 and 55. The said score or fold lines 54 and 55 respectively hingedly connect to the panel 50 tucking flaps 56 and 57. Each of the tucking flaps 56 and 57 has respectively, hingedly connected thereto through score or fold lines 58 and 59, spacer flaps 60 and 61. The panels 51 and 52 together constitutes the cover for the carton with the panel 52 having its ends defined by score or fold lines 62 and 63 while the ends of the panel 51 are cut lines in alignment with the score or fold lines 62 and 63 as well as in alignment with score or fold lines 54 and 55 disclosed in the drawings as extensions of the bottom panel score or fold

lines 17 and 19. The score or fold lines 62 and 63 respectively hingedly connect to the panel 52 flaps 64 and 65 which are substantially triangular in area forming in the closed carton cover side flanges and in the display position of said carton the supporting easel. The said flaps 64 and 65 are respectively provided with a diagonal score or fold line 66 and 67 thereby forming within each flap 64 and 65 a triangular area to each of which is applied adhesive 68 and 69, whereby the cover front flange is attached to the side flanges as will later be made clear. The panel 53 in the assembled carton constitutes when closed the cover front flange and when open on display ties the easel flaps to one another and this panel 53 has its ends defined by score or fold lines 70 and 71 respectively in alignment with the cover panel score or fold lines 62 and 63. The score or fold lines 70 and 71 respectively hingedly connect to the ends of the panel 53 glue flaps 72 and 73 which are adhesively secured to the adhesive carrying portion of flaps 64 and 65.

The side wall extensions 20 and 21 are substantially identical and it is believed sufficient if but one of them be described in detail.

Accordingly extension 20 is provided with a plurality of score or fold lines 74, 75, and 76 thereby providing between the fold or score line 17 and end of extension, panels 77, 78, 79 and 80. The panel 77 in the assembled carton forms the side wall outer wall member and has one end defined by the cut line 81 and the other end defined by the score or fold line 82. The panel 78 constitutes the side wall top wall member and has its ends contoured, shown in the drawing as biased and indicated by reference characters 83 and 84. The contoured ends 83 and 84 serve a useful and decorative purpose since the length of the panel 78 at the end adjacent the outer wall member 77 is of a length equal thereto while the other end is reduced to the distance between the inner wall members of the front and back walls. The ends of the panel 79 are defined by score or fold lines 85 and 86 which respectively hingedly connect to the said inner wall panel spacing flaps 87 and 88. Beyond the spacing flaps the panel 79 carries locking tabs 89 and 90. The remaining panel 80 of the extension 20 constitutes a spacer tab and in the assembled carton spaces the lower ends of the inner and outer wall members from one another.

The adjacent ends of the front wall outer wall member 34 and the side wall outer wall member 77 respectively through their score or fold lines hingedly connect between them corner piece 91 provided with a diagonal score or fold line 92 whereby said corner piece forms, what is commercially known, as, a bellows corner. In practice and as will later be made clear the bellows corner takes the place of a tucking flap in assembly.

After the blank has been cut and scored as just described adhesive 68 and 69 is applied to the outer-most corners of the easel flaps 64 and 65 and adhesive 93 is applied to the surface of the front wall outer wall member panel 28. The blank then has the glue flap 32 folded on the score or fold line 27 onto the panels 30 and 31. At the same time the easel flaps 64 and 65 are folded respectively on the score or fold lines 62 and 63 onto the cover panel 52 and the portions of each of said flaps 64 and 65 beyond their respective score or fold lines 66 and 67 is bent or folded backward onto the under surface of said

flaps as seen in Fig. 3. Also at this time the cover front flange attaching flaps 72 and 73 are folded on their respective score or fold lines 70 and 71 onto the flange flap 53. The blank is at this time as illustrated in the upper half of Fig. 4.

At this time the blank is further folded by folding the front wall bottom wall panel 31 and front wall inner wall panel 30 about the score or fold line 25 thereby bringing the glue flap 30 into engagement with adhesive 93 on the front wall outer wall member panel. At the same time the cover flange panel 53 is folded on the score or fold line 49 to bring its flaps 72 and 73 into contact with the adhesive portions 68 and 69 of the easel flaps 64 and 65. The blank is now as illustrated in the lower half of Fig. 4 ready for shipment to the ultimate user.

It will be noted that the device as defined provides a carton or box having a hollow or double front wall and side walls together with a single back wall and a cover or lid. The blank of Fig. 6 sets up as illustrated in Fig. 7 to provide the remaining hollow or double back wall. This blank of Fig. 6 is essentially rectangular in area and is provided with a plurality of score or fold lines 94, 95, 96 and 97 thereby providing between them and the ends of the blank a plurality of panels, 98, 99, 100, 101 and 102. The ends of the panels 98, 99, 100 and 102 are defined by the sides of the blank while the ends of the panel 101 is defined by score or fold lines 103 and 104 which respectively hingedly connect thereto tucking tab 105 and 106. The panel 101 is further provided inwardly of its ends elongated apertures 107 and 108.

After the blank of Fig. 6 has been cut and scored as just described with the panel 102 folded onto the panel 101 about the fold or score line 97 adhesive (not shown) is applied to the now exposed surface thereof. Panels 98 and 99 are now folded on the score or fold line 95 to bring the panel 98 into contact with the adhesive of panel 102. It is in this condition that the blank of Fig. 6 is shipped to the user.

The user, upon receipt of the main blank in its folded form of the lower half of Fig. 4 and the blank of Fig. 6, folded as described and desiring to set up the carton for use, first opens the blank of Fig. 6 by causing panels 98 and 102, as a unit, and panel 100 to likewise assume a parallel relationship which results in rectangular tube as illustrated in Fig. 7. In this set-up position the panel 101 constitutes the front wall member of the carton back wall with the panel 100 forming the top wall thereof and panels 98 and 102, as a unit, forming the bottom wall. The remaining panel 99 cooperates with the panel 50 of the main blank for providing the back wall outer wall member. The set-up of the blank of Fig. 6 is completed by bending forward the tabs 105 and 106.

The user then turns to the main blank and raises the back wall outer wall member 50 to be normal to the base 15 whereupon the set-up supplementary blank, assembly of Fig. 7, is placed in the position illustrated in Fig. 8. The front wall is then raised from its collapsed position to have the front wall outer wall member 28 normal to the base 15. The illustration in Fig. 8 is contrary to this and discloses, for the purpose of clearness, the front wall in its flat position while one side wall is shown as partly erected. The raising of the front wall automatically opens up the said wall, whereupon the inner wall member 30 is disposed parallel to the outer wall mem-

ber 28 with the top wall 29 and bottom wall 31 separating the same. The tucking flaps 39 and 40 are then arranged to be transverse of the base member, first the one side of the carton and then at the other. The spacer flaps 41 and 60, for example, are then bent to be parallel to the carton base or bottom 15. The end wall extension, 20 for example is then raised to be normal to the bottom as seen for example in Fig. 8. This automatically causes the bellows corner 71 to be folded on itself and disposed transversely of the base. The side wall spacer flaps 87 and 88 are then or have been previously folded to be normal to the inner wall member panel 79 whereupon 15 the remaining flaps 78, 79, and 80 are each folded to be normal to its adjacent flap thereby completing the set-up of the side wall.

The second side wall is assembled in the identical manner. The top or cover of the carton is 20 set-up by merely lifting the cover front flange panel 53 from its position in Fig. 4 to that illustrated in Fig. 8 thereby bringing the cover side wall panels or easel panels 64 and 65 to their operative positions as illustrated in Fig. 8.

Upon filling the carton with the desired goods 25 the cover is closed as illustrated in Fig. 1 and then shipped. The recipient of the package, in order to display the goods, raises the cover and 30 backwardly folds the same thereby bringing the panel 51 of the cover into engagement with the outer surface of the back wall outer wall member 50. Then continues to backwardly fold or "break-back" the cover on the score or fold line 48 which brings the outer surface of the cover 35 panel 52 into contact with the under-surface of the carton base or bottom 15 to the position illustrated in Fig. 2. The carton is then in the position simulating its support on an easel or 40 upwardly inclining with respect to the supporting counter.

From the foregoing it will now be appreciated 45 that there has been provided a carton or box having four hollow walls capable of use as a sturdy shipping container and has an attractive merchandise display carton.

This invention is capable of various modifications both as to the shape of blanks and the details thereof whereby additional strength or ease of set-up may be varied. The modification 50 illustrated in Figs. 9 and 10 takes the place of the supplementary blank illustrated in Figs. 6 and 7 and at the same time combines therewith a portion of the blank of Fig. 3 and requiring a modification therein. One reason for the modification of these blanks is the size of the resulting carton should it require a main blank of greater length than cardboard or the like available or of a length greater than the capacity of the machine on which blanks are formed. Accordingly the blank of Fig. 9 incorporates the back wall of the carton proper 55 together with the cover for the carton and accordingly the main blank of Fig. 3 would be modified to the extent of eliminating from it that portion thereof to the right of score or fold line 47 and including the panels 51, 52, and 53 together with the parts carried thereby.

Specifically, the blank of Fig. 9 is provided with 60 score or fold lines 109, 110, 111, 112, 113, 114, 115, 116, and 117 thereby providing panels 118, 119, 120, 121, 122, 123, 124, 125, 126, and 127 which take place of similar panels and fold lines in the 65 blanks of Figs. 3 and 6. In this modification there is illustrated a tubular tucking flap or side wall reinforcement which is formed to be rectangular in cross-section from extensions 128,

129, 130, 131, and 132 of the panels 118 to 122, inclusive. In this blank of Fig. 9 a modified cover side and front flange construction is illustrated. This modified construction is adapted to be knocked-down as distinguished from a glue construction described above. Accordingly the easel flaps 64 and 65 have hingedly connected thereto through score or fold lines 133 and 134 flaps 135 and 136 each provided within its border with elongate apertures 137 and 138. To cooperate with said flaps 135 and 136 the panel 127 is formed with locking tongues 139 and 140.

After the blank has been cut and scored as above described and illustrated in the upper half of Fig. 9 adhesive 141 is applied to the panel 123 and the panels 118, 119, and 120 folded on the score or fold line 111, to bring them into face contact with the panels 121, 122, and 123 and thereby the adhesive 141 for securing panels 118 and 123 to one another.

The blank of Fig. 9 is set-up in the same manner as the blank of Fig. 6 to provide a tube having a rectangular hollow construction whereupon the tubular tucking flaps are arranged as shown at the right and end of Fig. 10. The cover may be assembled at this time or may be assembled after the carton has been otherwise completely set-up and the two blanks joined together. The setting up of the cover is as follows:

Easel flaps 64 and 65 are folded to be normal to the cover panel 124 whereupon the flaps 137 and 138 folded to be normal to the easel flaps and transverse of the cover panel. Panels 126 and 127 are then folded on the score or fold line 116 to lie against the said flaps 135 and 136 and have the locking tongues 139 and 140 respectively disposed in the elongated apertures 137 and 138. The score or fold line 117 is employed to assist in the insertion of the locking tongue 139 and 140 into the apertures 137 and 138.

The blanks or subassemblies of the blanks of Fig. 10 and the modified blank of Fig. 3 are assembled into a carton in the same manner as above described.

In each of the cartons heretofore described the fourth or back wall of the carton was first assembled and the other walls folded to retain the same in position. In the construction illustrated in the modification in Figs. 11 to 14, inclusive, the reverse is true, in that the carton is set-up and the fourth wall inserted. In this modification the carton itself is illustrated as having a rectangular tucking flap instead of the auxiliary blank having this corner reinforcement. In this modification the cover is shown formed as that in the blank of Fig. 3 but it is to be understood that a construction similar to that illustrated in Fig. 9 may be substituted or this construction may be substituted for that of Fig. 3 since each of these types of lock forming constructions is well known, that illustrated in Fig. 3 being commercially known as a "Beers construction," while that illustrated in Fig. 9 is commercially known as a "hardware lock."

The only difference between the blanks of Figs. 11 and 3 is that the tucking flaps 56 and 57 are each provided with an extension including panels 142, 143, and 144 the latter of which is provided with adhesive 145 for attaching it to the back wall panel 50 so that the rectangular tucking flap has connection therewith. This blank of Fig. 11 is further modified in that its side wall inner wall members and top wall member are devoid of the spacing flap 87 and extend to the outer wall member of the back wall.

Substantially the only modification in the blank of Fig. 12 over that of Fig. 6 is that the top wall member panel 100 is provided with ears 146 and 147 which are given the contour of the ends of the back wall top wall member since they take its place in the assembly of the blanks.

As is noted above in this modification the main carton is first assembled and the supplementary wall is then assembled and merely inserted between the inner wall members of the carton side walls and is held in position by locking tabs 148 and 149 extending therefrom into the elongated aperture in the side wall inner wall members as illustrated clearly in Fig. 14.

From the foregoing it will now be appreciated that there has been provided a carton or box adapted to fulfill the objects initially set forth.

What is claimed is:

1. In a carton of the class described a main blank forming the carton proper comprising a bottom panel, a hollow front and hollow side walls and a solid back wall upstanding from said base, said hollow front and side walls being formed of articulated outer, inner and top wall members, an auxiliary blank forming a hollow back wall of articulated spaced apart outer and inner wall members joined by a top wall member with said hollow wall outer and inner wall members spaced from one another a distance as determined by the top wall member and with said hollow wall back wall outer wall member of a length to fit between the carton proper side wall outer wall members and in face contact with the main carton solid back wall and said hollow wall back wall inner wall member of a length to fit, at least, between the side wall inner wall members and with said hollow back wall inner and outer wall members upstanding from the carton proper bottom panel substantially to the height of the carton proper front, side and back walls, interengaging means on said hollow back wall and hollow side walls for securing the said walls in position, and a cover hingedly carried by one of said back walls for closing the carton.

2. In a carton of the class described a main blank forming the carton proper comprising a bottom panel, a hollow front and hollow side walls and a solid back wall upstanding from said base, said hollow front and side walls being formed of articulated outer, inner and top wall members, an auxiliary blank forming a hollow back wall of articulated spaced apart outer and inner wall members joined by a top wall member with said hollow wall outer and inner wall members spaced from one another a distance as determined by the top wall member and with said hollow wall back wall outer wall member of a length to fit between the carton proper side wall outer wall members and in face contact with the main carton solid back wall and said hollow wall back wall inner wall member of a length to fit, at least, between the side wall inner wall members and with said hollow back wall inner and outer wall members upstanding from the carton proper bottom panel substantially to the height of the carton proper front, side and back walls, interengaging means on said hollow back wall and hollow side walls for securing the said walls in position, and a cover hingedly carried by one of said back walls for closing the carton, said cover having a depending flange along one edge thereof for engaging the carton front wall when closed, depending side flanges from said cover for a portion of said cover sides rearwardly of the cover front flange and inclining upwardly from the ends

thereof, and said cover having a break-back score therein at a point beyond the side flanges so that the cover may be arranged to be below and in contact with the carton bottom undersurface to have its flanges depend and act as an easel stand.

3. In a carton of the class described formed from a main and an auxiliary blank, said main blank including a bottom panel with extensions from each side thereof to form a front wall, a back wall and side walls, said front and side walls extensions each being subdivided by score or fold lines into a plurality of panels to provide walls of inner and outer wall members, a top wall member and a bottom wall member or spacing panel, said front wall extension having a glued flap projecting from its last mentioned panel secured to the front wall outer wall member so that said front wall has its inner, outer and top wall members articulated to one another, the 20 back wall extension being subdivided to provide a back wall member, a cover and cover flanges, said auxiliary blank being subdivided to provide an auxiliary back wall including an inner and an outer wall member and a top and a bottom wall member with said auxiliary back wall outer wall member of a length to fit between the carton proper side wall outer wall members and in face contact with the main carton back wall and said auxiliary back wall inner wall member of a length to fit, at least, between the side wall inner wall members and with said auxiliary back wall inner and outer wall members upstanding from the carton proper bottom panel substantially to the height of the carton proper front, side and back walls, and means associated with the auxiliary back wall member and main blank side walls mounting and retaining the auxiliary blank in operative position.

4. In a carton of the class described formed of a main and an auxiliary blank, said main blank forming the carton proper including a bottom panel with a hollow articulated front wall, hollow side walls formed from extensions from the bottom panel scored to form inner and outer wall members with a top wall member therebetween and spacing flaps at the outer ends of said side walls inner wall members, a back wall hingedly connected to the bottom panel, said front, side and back walls extending upwardly from the bottom panel, said auxiliary blank forming a hollow back wall and cover or lid for the carton and which auxiliary blank back wall includes inner and outer wall members and top and bottom wall members, tucking flaps from the ends of the auxiliary blank back wall hingedly connected to its inner and outer wall members, said tucking flaps having their upper and lower edges connected to one another in spaced apart relation corresponding to the spacing of the auxiliary blank back wall inner and outer wall members so that the said tucking flaps are substantially rectangular in vertical cross section, and cooperating means on said auxiliary blank back wall and main blank side walls securing the parts in operative positions.

5. In a carton of the class described a first blank forming in the erected carton a bottom and upstanding front, side and back walls, said front and side walls each formed of a hollow construction and including a front and a back wall member joined by a top wall member separating said front and back wall members, certain of said front and side walls having a glue flap at the lower ends of their inner wall members whereby

said walls are hingedly connected to the carton bottom for erection from a flat to an upstanding position, an auxiliary blank forming in the erected carton an auxiliary back wall disposed on the carton bottom to upstand to the height of the carton front, side and back walls, said auxiliary back wall having spaced apart inner and outer wall members and top and bottom wall members, interengaging means on said blanks securing the auxiliary back wall in position with the top wall members of the carton front and side walls in substantially the same plane as the top wall member of the auxiliary back wall and with the auxiliary back wall outer wall member in face contact with the carton main back wall, and a cover hingedly connected to one of said blanks for swinging movement toward the said top wall members.

6. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom, spacer flaps carried by said tucking flaps, said tucking flaps with their spacing flaps enfolded by the side walls inner, outer and top wall members, a lid articulated to said back wall including flanges at the free end thereof and for a portion along the sides thereof, said flanges having their adjacent ends arranged interconnected to form lid depending flanges, said lid having a break-back score transversely thereof at the inner ends of its side flanges, a second blank forming in the erected carton a back wall having articulated inner, outer, top and bottom wall members and a glue member attached to the bottom wall member disposed on the carton proper bottom to upstand to a height substantially equal to the height of the walls of the carton proper and in face contact with the back wall of the carton proper, tucking flaps at the outer ends of the back wall inner wall member enfolded by the side wall inner and outer wall members, and interlocking means on said back wall inner wall member and said side wall inner wall members locking the carton in assembled position.

7. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom, spacer flaps carried by said tucking flaps, said tucking flaps with their spacing flaps enfolded by the side walls inner, outer and top wall members, a lid articulated to said back wall including flanges at the free end thereof and for a portion along the sides thereof, said flanges having their adjacent ends arranged interconnected to form lid depending flanges, said lid having a break-back score transversely thereof at the inner ends of its side flanges, a second blank forming in the erected carton a back wall having articulated inner, outer, top and bottom wall

members and a glue member attached to the bottom wall member disposed on the carton proper bottom to upstand to a height substantially equal to the height of the walls of the carton proper and in face contact with the back wall of the carton proper, tucking flaps at the outer ends of the back wall inner wall member enfolded by the side wall inner and outer wall member, and interlocking means on said back wall inner wall member and said side wall inner wall members for locking the carton in assembled position, comprising a slit in each of said side wall inner wall members and tongues projecting from the ends of the back wall inner wall member disposed in said slits.

8. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom, spacer flaps carried by said tucking flaps, said tucking flaps with their spacing flaps enfolded by the side wall inner, outer and top wall members, a second blank forming in the erected carton a back wall having articulated inner, outer, top and bottom wall members and a glue member attached to the carton lid, said back wall disposed on the carton bottom with the back wall outer wall member in face contact with the carton back wall to upstand from the carton bottom to the height of the carton front, side and back walls, a lid articulated to said back wall outer wall member including flanges at the free end thereof and for a portion along the sides thereof, said flanges having their adjacent ends interconnected to form lid depending flanges, said lid having a break-back score transversely thereof at the inner ends of its side flanges, and interlocking means on said back wall inner wall member and said side wall inner wall members locking the carton in assembled position.

9. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom, spacer flaps carried by said tucking flaps, said tucking flaps with their spacing flaps enfolded by the side wall inner, outer and top wall members, a second blank forming in the erected carton a back wall having articulated inner, outer, top and bottom wall members and a glue member attached to the carton lid, said back wall disposed on the carton bottom with the back wall outer wall member in face contact with the carton back wall to upstand from the carton bottom to the height of the carton front, side and back walls, a lid articulated to said back wall outer wall member including flanges at the free end thereof and for a portion along the sides thereof, said flanges having their adjacent ends interconnected to form lid depending flanges, said lid having a break-back score transversely thereof at the inner ends of

its side flanges, and interlocking means on said back wall inner wall member and said side wall inner wall members locking the carton in assembled position, comprising a slit in each of said side wall inner wall members and tongues projecting from the ends of the back wall inner wall member disposed in said slits.

10. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom toward one another, spacer flaps carried by said tucking flaps, said tucking flaps with their spacer flaps enfolded by the side wall inner, outer and top wall members, a second blank forming in the erected carton an auxiliary back wall and lid, said auxiliary back wall having articulated inner, outer, top and bottom wall members and a glue member attached to the carton lid, said auxiliary back wall being disposed on the carton bottom adjacent the carton back wall and upstanding to the height of the carton front, side and back walls, tucking flaps from the ends of the auxiliary back wall having a rectangular cross section corresponding to the interior of the side walls and formed from extension flaps articulated to the auxiliary back wall inner and outer wall members with each tucking flap having a top and a bottom between its extension flaps, said tucking flaps of the auxiliary back wall being enfolded by the side wall inner, outer and top wall members for retaining the auxiliary back wall in position, said lid being articulated to said auxiliary back wall outer wall member and including flanges at the free end thereof for a distance along the sides thereof from said free end flange, said flanges having their adjacent ends arranged for interconnection to form lid depending flanges, said lid having a break-back score transversely thereof at the inner ends of its side flanges, and additional interlocking means on said auxiliary back wall inner wall member and said side walls inner wall members locking the blanks in carton assembled position.

11. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner wall member and back wall disposed transversely of the bottom toward one another, spacer flaps carried by said tucking flaps, said tucking flaps with their spacer flaps enfolded by the side wall's inner, outer and top wall members, a second blank forming in the erected carton an auxiliary back wall and lid, said auxiliary back wall having articulated inner, outer, top and bottom wall members and a glue member attached to the carton lid, said auxiliary back wall being disposed on the carton bottom adjacent the carton back wall and upstanding to the height of the carton front, side and back walls, tucking flaps from the ends of the auxiliary back wall having a rectangular cross section cor-

responding to the interior of the side walls and formed from extension flaps articulated to the auxiliary back wall inner and outer wall members with each tucking flap having a top and a bottom between its extension flaps, said tucking flaps of the auxiliary back wall being enfolded by the side wall inner, outer and top wall members for retaining the auxiliary back wall in position, said lid being articulated to said auxiliary back wall outer wall member and including flanges at the free end thereof from said free end flap for a distance along the sides thereof, said flanges having their adjacent ends interconnected to form lid depending flanges, said lid having a break-back score transversely thereof at the inner ends of its side flanges, and additional interlocking means on said auxiliary back wall inner wall member and said side walls inner wall members locking the carton assembled position, comprising slits in one of said walls inner wall members and tongues on the other of said walls inner wall members received in said slits.

12. In a carton of the class described a first blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner and outer wall members and back wall disposed transversely of the bottom, the tucking flaps from the back wall each being formed from an extension thereof subdivided into panels articulated to one another and the back wall so that when transversely of the bottom each flap has a rectangular cross section corresponding to the interior of the side wall enfolded it, a lid articulated to said back wall including flanges at free end thereof and for a portion along the sides thereof, said flanges having their adjacent ends interconnected to form lid depending flanges, said lid having a break-back score transversely thereof at the inner ends of its side flanges, a second blank forming in the erected carton a hollow back wall having articulated inner, outer and top wall members and glue flaps articulated to the inner and outer wall members secured to one another, said hollow back wall of the second blank disposed on the carton bottom between the side wall inner wall members with its outer wall member in face contact with the carton back wall and upstanding substantially to the height of the carton proper front, side and back walls, and interlocking means on said back wall inner wall member and said side wall inner wall members locking the back wall in position.

13. In a carton of the class described a first

60

blank forming in the erected carton a bottom and upstanding front, side and back walls, said front and side walls each comprising articulated outer wall member, top wall member, inner wall member and bottom wall member or spacer member, said front wall having a glue flap articulated to its bottom wall member and attached to its outer wall member, tucking flaps at the ends of the front wall inner and outer wall members and back wall disposed transversely of the bottom, the tucking flaps from the back wall each being formed from an extension thereof subdivided into panels articulated to one another and the back wall so that when transversely of the bottom each flap has a rectangular cross section corresponding to the interior of the side wall enfolded it, a lid articulated to said back wall including flanges at free end thereof and for a portion along the sides thereof, said flanges having their adjacent ends interconnected to form lid depending flanges, said lid having a break-back score transversely thereof at the inner ends of its side flanges, a second blank forming in the erected carton a hollow back wall having articulated inner, outer and top wall members and glue flaps articulated to the inner and outer wall members secured to one another, said hollow back wall of the second blank disposed on the carton bottom between the side wall inner wall members with its outer wall member in face contact with the carton back wall and upstanding substantially to the height of the carton proper front, side and back walls, and interlocking means on said back wall inner wall member and said side wall inner wall members locking the back wall in position, comprising a slit in each side wall inner wall members and tongues projecting from the ends of the hollow back wall inner wall member.

WILLIAM P. FRANKENSTEIN.
